UNITED STATES PATENT OFFICE.

WILLIAM DALTON, OF SCHENECTADY, NEW YORK, ASSIGNOR TO
AMERICAN LOCOMOTIVE COMPANY, OF NEW YORK, N. Y., A
CORPORATION OF NEW YORK.

CUSHIONING APPLIANCE FOR LOCOMOTIVES.

No. 841,379.

Specification of Letters Patent.

Patented Jan. 15, 1907.

Application filed August 31, 1906. Serial No. 332,735.

To all whom it may concern:

Be it known that I, WILLIAM DALTON, of Schenectady, in the county of Schenectady and State of New York, have invented a certain new and useful Improvement in Cushioning Appliances for Locomotives, of which improvement the following is a specification.

The object of my invention is to provide means for the prevention of the jars, shocks, and injury to track-rails resultant upon the heavy blows struck thereon in the side lurching or abrupt lateral movement of locomotives when running at high speeds. This destructive action, while exerted to a substantial degree in the operation of steam-locomotives, is not as great as in the case of electric locomotives, by reason of the fact that in the former the center of gravity of the machine is above the spring suspension, and the springs on opposite sides being comparatively close together, as the frames are located inside the wheels, side blows on the rails caused by lurching of the locomotive are in a measure cushioned by the pressure of the locomotive on the spring, which causes a portion of the blow to be expended in downward pressure on the rail, the action being that of an inverted pendulum. In electric locomotives the heavy motor-weights are hung between the wheels and the center of gravity is below the spring suspension, and under these conditions lurching or abrupt lateral movement of the locomotive exerts heavy side blows on the rails, which are injurious to them and to the locomotive.

My invention is designed to so cushion the side blows referred to that the impact of the locomotive upon the rail will be reduced to such an extent as to prevent the objectionable results experienced at high speeds in present practice.

The improvement claimed is hereinafter fully set forth.

In the accompanying drawings, Figure 1 is a view, partly in section, showing an axle of an electric locomotive, with its wheels, axle-boxes, and pedestal-shoes, illustrating an application of my invention; Fig. 2, a side view in elevation of a portion of the locomotive frame, showing an axle-box and wheel; Fig. 3, a horizontal section, on an enlarged scale, through a pair of pedestal jaws, shoes, and an adjacent wheel-hub; Fig. 4, a similar section,

on a further enlarged scale, through one of the jaws and shoes; Fig. 5, a vertical section through one of the shoes on the line *a a* of Fig. 3, and Fig. 6 an outer end view in elevation of the shoe.

My invention is herein exemplified as applied in connection with an axle 2 of an electric locomotive, upon which wheels 4 are secured and which is journaled in axle-boxes 3 in the ordinary manner. Pairs of lateral flanges 3^b and 3^c are formed in the axle-boxes, and pedestal-shoes 5^e are fitted in the spaces 6^c or side recesses between said flanges. Each of the shoes 5^e is provided with lateral flanges extending on opposite sides of a pair of vertical pedestal-jaws 5^b, fixed on and constituting part of one of the side frame members of the locomotive, the construction providing for vertical movement of the pedestal jaws and shoes relatively to the axle-boxes and being as thus far described one which is well known in ordinary practice.

In the practice of my invention as herein illustrated in structural detail, which has been found desirably adaptable in actual service, a vertical recess 5^f is formed in one of the side flanges of each of the pedestal-shoes 5^e, and a plate-spring 10^a, having one or more leaves, as desired, is fitted in each of said recesses. The ends of the spring 10^a or of the outer leaf, if more than one is used, bear on seats 5^g at the ends of the recess 5^f, and the middle portion of the spring or of the inner leaf, if more than one is used, bears against the adjacent side of the pedestal-jaw 5^b, as clearly shown in Fig. 5. Sufficient clearance is left between the side flange of the shoe on the outside of the groove 5^f and the pedestal-jaw to admit of the lateral movement of the axle-box and shoe and the compression of the spring in resisting such lateral movement in direction toward it, as most clearly appears by reference to Fig. 4. As will be obvious to those familiar with locomotive construction, the shoes 5^e are interposed between the axle-boxes and pedestal-jaws merely to act as liners or bearing-surfaces for the axle-boxes, and therefore the location of the springs 10^a in the inner flanges of the axle-boxes instead of in the shoes, as in the instance shown, would not involve any departure from the spirit and operative principle of my invention.

It will be seen that under the construction above described the heavy side blows upon the rails resultant upon lurching or abrupt lateral movement of the locomotives are in each direction resisted and cushioned by the springs 10^a on the side of the locomotive toward which its movement is directed, and the resistance of the springs may be adjusted to meet any determined conditions by the proper proportioning of the thickness of the metal of the springs, the number of their leaves, and the degree of clearance between the inner flanges of the pedestal-shoes and the jaws. The improvement has in practice been found substantially effective and advantageous in the operation of electric locomotives at speeds ranging from sixty to ninety miles per hour and is also adaptable without variation of operative principle in the operation of steam-locomotives at high speeds.

I claim as my invention and desire to secure by Letters Patent—

1. The combination of an axle, axle-boxes in which said axle is journaled, shoes fitting lateral recesses in said axle-boxes, frame pedestal-jaws in which said shoes are fitted with the capacity of lateral movement, and plates springs interposed vertically between the inner

sides of the pedestal-jaws and the adjacent portions of the shoes. 30

2. The combination of an axle, axle-boxes in which said axle is journaled, pedestal-jaws located on opposite sides of the axle-boxes, shoes fitting in lateral recesses in the axle-boxes and having lateral flanges extending on opposite sides of the pedestal-jaws and providing space or clearance on the inner sides of said jaws, and springs interposed between and abutting on the inner sides of said jaws and the adjacent flanges of the shoes. 40

3. The combination of an axle, axle-boxes in which said axle is journaled, pedestal-jaws located on opposite sides of the axle-boxes, pedestal-shoes fitting in lateral recesses in the axle-boxes and having lateral flanges extending on opposite sides of the pedestal-jaws and providing space or clearance on the inner sides of said jaws, there being spring-seats formed in vertical recesses in the flanges of the shoes on the inner sides of the jaws, and springs bearing on said seats and on the adjacent sides of the jaws. 45 50
